FURNACE

Carl A. Maxwell, Teaneck, N. J., assignor to
Fuller Lehigh Company, New York, N. Y., a cor-
poration of Delaware

Application March 31, 1931, Serial No. 526,625

11 Claims. (Cl. 122—6)

My invention relates to furnaces, particularly furnaces having water cooled walls. The invention is especially useful in connection with furnaces in which fuel is burned in finely comminuted condition and in which high temperatures are produced.

One object of the invention is to provide support for the water cooling system of a furnace wall. A second object is to provide restraining means against lateral movement of a furnace wall. A further object is the provision of such support and such restraint in a manner which will permit limited horizontal movement of the wall. Other objects will be apparent upon consideration of the following specification:

One form of the invention is illustrated in the accompanying drawing in which—

Figure 1 is a vertical section through the lower part of a furnace constructed in accordance with the invention,

Fig. 2 is a section on the line II—II of Figure 1,

Fig. 3 is a section on the line III—III through one of the supports shown in Figure 1, and

Fig. 4 is a section on the line IV—IV of Fig. 3.

The furnace shown comprises a floor 10 which is illustrated as formed of refractory material. Walls 11 are provided which limit the horizontal extent of the furnace, and water tubes 12 are disposed in the walls for cooling the same. The water tubes in each wall extend below the floor and terminate in a header 13 in the plane of the wall, which lies in a substantially horizontal position. One such header is employed in connection with each wall.

A horizontally movable support 14 is provided for each header 13, horizontal movement being provided for in any known or convenient manner, for instance, by means of rollers. As here illustrated a roller support in the form of a ball bearing support is provided for each header. Thus, in the present construction, the headers 13 rest in one or more saddles 15 and a horizontal plate 16 supports each saddle. A horizontal bed-plate 17 lies beneath the first-named plate, and bearing balls 18 are carried upon the bed-plate supporting the first-named plate 16 with its load.

* It will be obvious that the support is adapted to carry the header and permit movement in substantially any horizontal direction, since the balls roll upon the bed-plate and permit the horizontal plate 16 which carries the saddle 15 to roll over them.

The bed-plate 17 here shown is dished, thereby limiting the extent to which the bearing balls 18 may roll. Furthermore, the horizontal saddle-

carrying plate 16 has downwardly turned flanges 19, which will limit the extent of its travel over the balls, at the same time affording some protection against falling grit and dirt entering the space occupied by the balls.

Resilient restraining means are associated with each header and tend to maintain the wall against the floor and to prevent movement of the header outwardly from the furnace. Obviously, a variety of such means may be employed to produce this effect.

In the present embodiment the resilient restraining means take the form of a spring, and as here illustrated, two springs 20 are provided having a strap 21 passing through their centers and surrounding the header 13 whose movement they restrain. The springs 20 act in compression by bearing upon the flange 22 of a member supporting the furnace wall 10, as will be apparent at once from inspection of the accompanying drawing. In the event of expansion of the furnace floor, or of any material resting upon it, outward movement of the furnace walls will be restrained by means of the resilient restraining means described. The walls are held against expansion of the floor by means of the springs, and bear against the seals. Should the thrust overcome the springs, the walls will be able to move in a horizontal direction without deflection or distortion of the tubes.

From the foregoing, it will be evident that the invention is particularly useful in connection with slag tap furnaces, and it will be seen that the drawing illustrates such a furnace.

I do not consider the embodiment described and illustrated in the accompanying drawing as limiting my invention, since it is presented merely to indicate how the invention may be employed. With this understanding, therefore,

I claim:

1. In a furnace for burning a slag-forming fuel, a bottom, bottom supported side walls enclosing said bottom, means for maintaining said side walls in contact with the edges of said bottom to prevent leakage of slag between said bottom and said walls, separate supports for each of said side walls and for said bottom, and means cooperating with said supports to permit outward movement of the walls resulting from horizontal expansion of said walls and said bottom while a leak-preventing contact between said walls and said bottom is maintained.

2. In a furnace for burning a slag-forming fuel, a bottom adapted to sustain a pool of molten slag, bottom supported side walls enclosing

said bottom, means for continuously maintaining said side walls in nonleaking contact with said bottom, supports for said bottom, and separate rolling supports for each of said walls.

5. Fluid heat exchange apparatus constituting a slag tap furnace and comprising, bottom supported furnace walls including rows of fluid conducting wall tubes, separate headers for said walls having the lower ends of the tubes connected thereto, separate rolling supports for said headers facilitating expansion movements of the headers in any horizontal direction, a refractory slag tap furnace floor positioned between the walls and above said headers, separate supports for said floor, and spring actuated devices acting directly on the headers to tend to pull them against the marginal portions of the floor, said spring devices tending to maintain a slag tight joint between the floor and said walls to prevent leakage of slag maintained in a pool on the floor of the furnace.

4. Fluid heat exchange apparatus constituting a slag tap furnace and comprising, a refractory floor for maintaining a body of slag in the furnace, a support for the floor, separate headers at opposite sides of the floor, rolling supports for the headers, furnace walls extending upwardly from the headers and including wall tubes connected therewith, and spring means acting on one of said headers to exert a force inwardly of the furnace on the superposed furnace wall, each header supporting the superposed wall in contact with the slag body.

5. Fluid heat exchange apparatus constituting a slag tap furnace and comprising, a bottom supported furnace wall including a row of fluid conducting wall tubes, a header for said wall having the lower ends of the tubes connected thereto, separate rolling supports for said header facilitating expansion movements of the header in any horizontal direction, a refractory slag tap furnace floor, separate supports for said floor, and spring actuated devices acting to tend to pull the wall inwardly of the furnace and against a marginal portion of the floor, said spring devices tending to maintain a slag tight joint between the floor and said wall to prevent leakage of slag maintained in a pool on the floor of the furnace.

6. Fluid heat exchange apparatus constituting a slag tap furnace and comprising a refractory floor for maintaining a body of slag in the furnace, a support for the floor, a wall tube header at the side of the floor, rolling supports for the header, a furnace wall extending upwardly from the header and including wall tubes connected therewith, and spring means acting on the header to exert a force inwardly of the furnace on the superposed furnace wall, the header supporting the superposed wall in contact with the slag body.

7. Fluid heat exchange apparatus constituting a slag tap furnace and comprising, bottom supported furnace walls including rows of fluid conducting wall cooling tubes, separate headers for

said walls having the lower ends of the tubes connected thereto, separate rolling supports for said headers facilitating expansion movements of the headers in any horizontal direction, a refractory slag tap furnace floor positioned between and contacting with the walls, separate supports for said floor, and spring actuated devices acting on the walls to tend to pull them inwardly of the furnace and against the marginal portions of the floor, said spring devices tending to maintain a slag tight joint between the floor and said walls to prevent leakage of slag maintained in a pool on the floor of the furnace.

8. In a slag tap boiler furnace, bottom supported furnace walls including refractory covered wall cooling tubes, a header connected to the lower ends of the tubes of each wall so as to support the tubes and the walls, a refractory slag supporting floor located between the walls and having a slag tight juncture with each wall, supports for the floor, separate rolling supports for the headers permitting each header to move horizontally independently of the floor, and restraining means to keep the walls in close contact with the floor.

9. Fluid heat exchange apparatus constituting a slag tap furnace and comprising, bottom supported furnace walls including rows of fluid conducting wall tubes, separate headers for said walls having the lower ends of the tubes connected thereto, separate rolling supports for said headers facilitating expansion movements of the headers in any horizontal direction, a refractory slag tap furnace floor positioned between the walls, separate supports for said floor, spring actuated devices acting on the walls to tend to pull them inwardly of the furnace and against the marginal portions of the floor, and means anchoring the spring devices to the floor supports, said spring devices tending to maintain a slag tight joint between the floor and said walls to prevent leakage of slag maintained in a pool on the floor of the furnace.

10. In a slag tap boiler furnace, bottom supported furnace walls including refractory covered wall cooling tubes, a header connected to the lower ends of the tubes of each wall so as to support the tubes and the walls, a refractory slag supporting floor located between the walls and having a slag tight juncture with each wall, fixed supports for the floor, rolling supports for the headers independent of the floor supports, means for periodically allowing accumulated molten slag to flow from the furnace, and restraining means to keep the walls in close contact with the floor.

11. In a slag tap furnace, a refractory floor adapted to support a pool of molten slag, a wall, water tubes in said wall for cooling the same, said water tubes extending below said floor, and a header in the plane of the wall in which said water tubes terminate, roller support for said header and restraining means to keep the wall in close contact with the furnace floor.

CARL A. MAXWELL.
